UNITED STATES PATENT OFFICE.

EDWARD POSSON, OF CHICAGO, ILLINOIS.

CAR-DOOR.

1,110,458.

Specification of Letters Patent. Patented Sept. 15, 1914.

Application filed October 31, 1912. Serial No. 728,872.

To all whom it may concern:

Be it known that I, EDWARD POSSON, a citizen of the United States, residing at Chicago, in the county of Cook and State 5 of Illinois, have invented certain new and useful Improvements in Car-Doors, of which the following is a specification.

The principal object of my invention is to provide a new and improved outside door 10 for railway freight cars.

Another object of my invention is to provide an improved grain-tight outside door for freight cars.

Still another object of my invention is 15 to provide improved means for operating such a door.

A further object of my invention is to provide means for fastening the door in closed position.

20 All these objects and others will be made apparent in the following specification and claims, taken in connection with the accompanying drawings.

For the purpose of clearly explaining the 25 nature of my invention I have illustrated one specific embodiment thereof in the accompanying drawings.

The invention is defined in the appended claims.

30 Referring to the drawings—Figure 1 is a side elevation of my improved door; Fig. 2 is a vertical section taken on the line 2—2 of Fig. 1; Fig. 3 is an enlarged section of the lower part of the door, taken on the line 2—2 35 of Fig. 1; Figs. 4, 5 and 6 are horizontal sections taken on the correspondingly numbered lines in Fig. 2; Fig. 7 is an elevation of certain parts at the lower right hand corner of the door as viewed in Fig. 1; Fig. 40 8 is an elevation of a latching tongue; Fig. 9 is an elevation of a handle and associated elements of apparatus; Fig. 10 is a horizontal section taken on the line 10—10 of Fig. 7; Fig. 11 is a horizontal section taken 45 on the line 11—11 of Fig. 7; Fig. 12 is a vertical section taken on the line 12—12 of Fig. 7; Fig. 13 is a vertical axial section taken on the line 13—13 of Fig. 7; Fig. 14 is a vertical section taken on the line 14—14 50 of Fig. 13; and Figs. 15, 16 and 17 are perspective views of certain interlocking parts shown in elevation in Fig. 9.

The side wall 20 of the freight car has the usual door opening adapted to be closed by the door, which is designated generally by

the reference numeral 21. The door opening is bounded at the sides by the posts 22 and 23, and at the bottom by the sheet metal plate 25 resting on the floor 24. Between the floor and the supporting side sill 26 lies the web 27 of a T-bar 27—28, whose head is 28. This T-bar extends below the door opening and for a considerable distance to the right thereof, and constitutes a supporting and guiding track for the door. At the 65 right, as viewed in Fig. 1, the web of the T-bar is cut away so as to leave tongues 29, which are bent down and bolted to the side wall. This part of the T-bar 27—28 has a series of perforations 109 adapted to be engaged by the teeth of the gear wheel 75. 70

The door post 22, against which the leading edge of the door closes, is reinforced by a sheet metal member 30, and the other door post 23 is reinforced by a sheet metal member 31. These members 30 and 31 have their inner edges turned in and seated in vertical channels that are rabbeted in the inside faces of the door posts. The member 30 has its outer portion folded back against the 80 door post, as designated 32, and then again folded, as designated 34, so as to form a socket 38 to receive the leading edge 40 of the door when it is closing. The space 38 is maintained by means of interposed washers 35, through which the bolts 36 pass. The extreme edge of the member 30 is doubled, as at 37, to give it a proper finish and stiffness. The outer edge of the sheet metal member 31 is folded back at right angles 85 and spaced from the door post 23, as indicated at 39, and the following edge of the door has secured thereto a channel piece 41 by means of the rivets 42. This channel strip engages the edge 39 of the member 31 90 when the door is closed. Over the top of the door opening is a wooden member 43, which has a channel cut on its outer face. This channel is overhung by a sheet metal lip 44, thus providing a slot or guide between 100 the members 43 and 44 for the upper edge of the door 21.

At the lower left hand edge of the door, as viewed in Fig. 1, there is a cast-iron bracket 45, with an extension piece 46 that 105 hooks under the head of the T-rail 27—28. This bracket carries a roller 47 to run upon the head 28 of the T-rail. At the other lower corner of the door there is another cast-iron bracket 48 with an extension part 110

103 that hooks under the head 28 of the T-rail guiding and supporting track. This bracket has a roller 49 engaging the rail 28. The head of the T-rail track is slightly reduced under the rollers 47 and 49 when the door is closed, as indicated at 104. These rollers are carried on members that go into sockets in the respective brackets 45 and 48. Shims can be introduced through the 10 slots 105 to adjust the height of the rollers 47 and 49 relatively to the door.

The sheet metal door 21 is strengthened in its lower part by transverse ribs 50. In its upper part there is an opening adapted 15 to be closed by the sub-door 51, which is strengthened by the transverse ribs 52. This sub-door moves in the lateral vertical guides 53. Just below the sub-door the main door is strengthened by the transverse ribs 54, 20 which, however, do not project out far enough to interfere with the vertical movement of the sub-door. At its top the door 21 carries an overhanging lip 55, which is engaged by the upper edge of the sub-door 25 when the latter is closed. The lower edge of the sub-door carries a hooked lip 56 that engages the stationary down-turned flange 57 when the sub-door is closed. The arm 58 has its forked ends 59 pivotally connected 30 with the sub-door 51, and at its lower end is the operating handle 60, whereby the sub-door may be raised and lowered.

A small opening in the lower part of the main door is adapted to be closed by a sub-door 61, which moves horizontally in the upper and lower guides 62 and 63. This sub-door 61 has a hooked lip 64 which closes its following edge, and its leading edge enters a stationary lip 65. Attached to the 40 sub-door 61 is a bracket 66, with a jaw 67 adapted to be engaged by a tongue 106 which depends from the bar 58. This bar also carries an inward projection 68 adapted to go into the socket 70 attached to the door 21. 45 This projection and socket have registering perforations 69 and 71, adapted to be engaged by the bolt 72 which slides in the socket 74. The remote end of the bolt 72 is bent down, as designated 73. When the door 50 is locked, this down-turned end 73 lies in the notch 102 of the bracket 48.

A gear wheel 75 has its teeth adapted to engage the perforations 109 in the T-rail. Thus the latter constitutes a kind of rack to 55 coöperate with said gear wheel, which wheel is cast integral with a cylindrical portion 76 bounded by a flange 77, as shown in Fig. 13. The bracket 48 is formed with a curved socket 78, bounded above and below by the 60 projecting jaws 79. The cylindrical member 76 fits in this socket and is retained by the block 80, which goes between the jaws 79 and is secured by the bolt 81. The gear wheel 75 also carries integrally therewith a 65 transverse sleeve 82, within which slides the

handle 83. Within the cylindrical member 76 is a space 84, with guides 88 for the plunger 85 carrying the head 86, under which is the spring 87 that causes the head to push against the bar 83. The inside of the sleeve 70 82 is beveled at 107, as indicated in Fig. 11. The ends of the bar 83 have rivets 89, so that the bar cannot escape from the sleeve.

The lower part 103 of the bracket 48 has a head 90, with its spindle 91 rotatably mounted therein. Pivoted to this rotatable head is a hasp 92 with a projection 93 adapted to enter a hole 94 in the handle 83. The hasp also has a tongue 95, perforated at 96, and this perforation is adapted, when the hasp 80 is closed, to register between two holes 97 on respective lugs that project out from the bracket 48. A latching member 98 pivoted on the bracket 48 carries a tongue 108 adapted to engage the registering holes 96 and 97. 85 The latch 98 is pivoted at 100, and a leaf spring 99 tends to hold it in normal operative position. Registering perforations 101 in the latch 98 and an adjacent lug that projects from the hasp facilitate fastening 90 the latch by means of an ordinary car door seal.

Supposing that the car is loaded with grain, and it is desired to unload the same and open the door, the seal through the 95 perforations 101 is broken, the latch raised, and the hasp thrown down. This permits the arm 73 on the bolt 72 to be thrown out, and then said bolt is pushed to the right, as viewed in Fig. 1. This unlocks the projection 68 from the socket 70 and permits the handle 60 to be pulled out, thus removing the tongue 106 from the socket 67 and permitting the sub-door 61 to be moved to the left. Thereupon the grain adjacent to the 105 door flows out through the small lower opening in the door 21. After the pressure has been relieved, the operator takes the handle 83 and rotates the gear 75, thus opening the main door 21. If the operator finds it inconvenient to carry the handle 83 clear around, he can give it half a revolution and then slide it lengthwise through the socket 28 alternately. After the main door is 110 opened, the remaining grain in the car can 115 be removed by usual well-known methods.

When it is desired to close the door, this is done by rotating the handle 83 in the appropriate direction. The upper sub-door 51 can be left open temporarily for introducing grain through a spout. The operation of completely locking the parts in closed relation will be readily understood from the foregoing description of how they are unlocked.

It will be seen that a single seal secures the latch that locks the main door, the operating handles, and both sub-doors. The lower edge of the door 21 lies inside of the T-head 28, and thus makes a grain-tight 130

closure across the bottom. The door also makes a grain-tight closure at its sides, as shown in Figs. 4 and 5.

I claim:—

5. 1. In a device of the class described, a main door, a vertically sliding sub-door on the upper part of the main door, a horizontally sliding sub-door below, a depending handle pivoted on the upper sub-door 10 and having a depending tongue adapted to engage the lower sub-door, and means to lock the handle in position.
2. In a device of the class described, a main door, a vertically sliding sub-door on 15 the upper part of the main door, a second sub-door below, a depending handle secured to the upper sub-door, a socket secured to the main door, said handle having a part adapted to engage said socket and another 20 part adapted to engage said lower sub-door, and means to lock said handle in position.
3. In a device of the class described, a door with an opening therethrough, a sub-door for said opening, a handle for manipulating the sub-door, said handle carrying a 25 projection with a perforation therethrough, a socket attached to the main door to receive said projection, said socket having registering perforations, a bolt to go through said 30 registering perforations, operating means attached to said bolt, and means to lock said operating means and thereby secure said main door and said sub-door against opening.
4. In a device of the class described, a main door, a sub-door on the upper part of 35 said main door, a second sub-door below, a depending handle secured to the upper sub-door, a socket attached to said main door, said handle having a part adapted to engage 40 said socket, another part adapted to engage said lower sub-door, said first named part and said socket having registering perforations, operating means attached to the bolt, and means to lock said operating means and 45 thereby secure said main door and both of said sub-doors against opening.
5. In a device of the class described, a door with an opening therethrough, a sub-
- door for said opening, a handle for manipulating the sub-door, a projection from the 50 handle with a perforation therethrough, a socket attached to the main door to receive said projection, said socket having registering perforations, a bolt to go through said 55 registering perforations, a handle attached to the bolt, an operating handle to manipulate the main door, and means to lock the operating handle over the bolt handle and thereby secure the main door and the sub-door against opening. 60
6. In a device of the class described, a main door, a vertically sliding sub door on the upper part of the main door, a horizontally sliding sub door below, a depending handle pivoted on the upper sub door, a 65 socket carried by said lower sub door, a tongue depending from said handle and engaging said socket, a projection from said handle engaging said main door, and means to lock said projection in position and thereby secure said main door and both of said 70 sub doors against opening.
7. In a device of the class described, a main door, a vertically sliding sub door on the upper part of the main door, a horizontally sliding sub door below, a depending handle pivoted on the upper sub door, a socket carried by said lower sub door, a tongue depending from said handle and engaging said socket, a projection from said 75 handle with a perforation therethrough, a socket attached to the main door to receive said projection, said socket having registering perforations, a bolt to go through said 80 registering perforations, a handle attached to the bolt, an operating handle to manipulate the main door, and means to lock the operating handle over the bolt handle and thereby secure the said main door and both of said sub doors against opening. 85
- 90

In testimony whereof, I have subscribed my name.

EDWARD POSSON.
